[57] CLAIM

The ornamental design for the combined faucet attachment and water filter, as shown and described.

DESCRIPTION

FIG. 1 is a perspective view of the combined faucet attachment and water filter showing one side, one end and the bottom thereof;

FIG. 2 is a perspective view of the combined faucet attachment and water filter showing the other side, other end and top thereof;

FIG. 3 is a side elevational view of the combined faucet attachment and water filter as shown in FIG. 1, the opposite side elevational view is a mirror image;

FIG. 4 is an end elevational view taken on line 4—4 of FIG. 3, the attachment portion is partially shown for clarity of illustration;

FIG. 5 is a cross-sectional view thereof, taken on line 5—5 of FIG. 3; and,

FIG. 6 is an opposite end view taken on line 6—6 of FIG. 3, the filter portion is shown separately for clarity of illustration.
